UNITED STATES PATENT OFFICE.

ANTHONY L. SHORE, OF MINNEAPOLIS, MINNESOTA.

PORTABLE DOOR LOCK AND ALARM.

SPECIFICATION forming part of Letters Patent No. 655,523, dated August 7, 1900.

Application filed April 21, 1900. Serial No. 13,726. (No model.)

To all whom it may concern:

Be it known that I, ANTHONY L. SHORE, a citizen of the United States, residing at Minneapolis, in the county of Hennepin and State 5 of Minnesota, have invented certain new and useful Improvements in Portable Door Locks and Alarms; and I do hereby declare the following to be a full, clear, and exact description of the invention, such as will enable others skilled in the art to which it appertains to make and use the same.

My present invention has for its object to provide an improved portable door-lock especially adapted for use by traveling men 15 and tourists or other persons who are obliged to travel from place to place, the device serving to secure the doors of their rooms in such manner that they cannot be opened by the manipulation of the ordinary door-lock.

To the above ends the invention consists of the novel devices and combinations of devices hereinafter described, and defined in the claims.

This invention relates to the same class of 25 door-locks or door-securing devices set forth in my pending application, Serial No. 6,677, filed February 27, 1900.

The present invention is illustrated in the accompanying drawings, wherein like characters indicate like parts throughout both views.

Figure 1 is a horizontal section through a portion of a door and a door-frame, showing my improved lock applied in working position thereto; and Fig. 2 is a similar view but 35 illustrating different positions of the parts.

The numeral 1 indicates a portion of an ordinary door, and the numeral 2 indicates a portion of an ordinary door-frame having the door-stop strip 3, against which the door 40 closes in the ordinary manner. In the construction illustrated in Fig. 1 the door-frame is also shown as provided with casings 4 5, while in the construction illustrated in Fig. 2 the inner side of the door-frame is shown as 45 extending flush with the inner surface of the door 1. In both views the numeral 6 indicates an ordinary latch-plate, having one or more passages 7 for the latch or lock bolt, the door-frame being recessed at 8 in line with the 50 said perforation 7.

Of the parts of the portable lock the character *a* indicates a screw-threaded stem, which

terminates at its inner end in a flattened section *a'*, having a laterally-projecting detent or lug *a''*. The flattened portion *a'* is adapted 55 to extend between the latch-plate 7 and the adjacent free portion of the door 1; and the detent *a''* is adapted to be inserted through the perforation 7 and into the recess 8. The said detent must of course be so applied while 60 the door is swung open. When the door is swung closed, the device is secured in position.

The character *b* indicates a reversible angle bracket or plate, which is perforated, as 65 shown at *b'*, and is provided with a foot or bent portion *b''*. In applying the device to a door which stands offset from its frame or from the casing thereof, as shown in Fig. 1, the foot *b''* of the bracket *b* is turned inward 70 for contact with the door, as shown in said Fig. 1. Where the casing is not provided or where the door and its frame extend flush at the inner side, the bracket *b* is applied, as shown in Fig. 2, with its foot *b''* turned outward. 75

Outward of the bracket *b* a securing head or knob is screwed onto the stem *a* and applied to clamp the angle-bracket *b* in working position.

An alarm device in connection with the above lock is desirable, and hence I employ a small bell *c* of the type used as bicycle-bells, and this is detachably applied to the stem *a*, being screwed onto the said stem. 85 For an important purpose a coiled spring *f* is applied between the bracket *b* and the knob or bell *c*, it being understood that the said bell is thus employed to serve the double function of an alarm and a stop. To actuate 90 the bell automatically when an attempt is made to open the door, a small bell-crank lever *g* is shown as pivoted to one section of the bell, one arm thereof being connected by a short link *g'* to the bell-actuating lever *f'*. 95 The other arm *g''* of the said bell-crank is so set that it normally engages or stands very close to the outer surface of the bracket or plate *b*, either as shown in Fig. 1 or as shown in Fig. 2. To lock the bell *c* in the position 100 in which it is adjusted, a thumb-nut *k* is preferably applied to the stem *a*, the same being normally screwed against the said bell, as shown in the drawings.

It is important to here note that the foot b^2 of the angle plate or bracket b stands at such distance from the perforation b' that when the said bracket is turned with its foot outward, as shown in Fig. 2, either the said bell or the thumb-nut k , according to which may be applied inward, clears or passes free of the said outturned foot portion. These relative dimensions are necessary in order to permit the said bracket b to be reversed.

The action will be substantially as follows: With the device applied either as shown in Fig. 1 or as shown in Fig. 2 the door may be moved slightly inward, and this movement is sufficient to cause the bracket b to engage and move the bell-crank g^2 , thereby imparting movement to the bell-actuating lever f' , with the result that the bell will be rung and an alarm given. However, but slight movement of the door is permitted, for the reason that the spring f is capable of but little compression, and when compressed to its limit becomes a rigid intermediate stop and prevents further opening movement of the door. The device above described is of course capable of considerable modification within the scope of my invention. For instance, if the alarm feature is not desired an ordinary knob or nut may be substituted for the bell. It will also be understood that even if the bell be provided the connections for actuating the same by the initial opening movement of the door may take various forms. The bell might be placed directly against or in contact with the angle-plate b , and the spring might be placed between the bell and the thumb-nut k , in which case by the initial opening movement of the door the bell-crank g g^2

would be actuated by engagement with the said thumb-nut.

What I claim, and desire to secure by Letters Patent of the United States, is as follows:

1. The combination with a detent-stem securable between the free edge of a closed door and its frame, of a spring and a bell on the said stem, and a bell-actuating connection acted upon by the initial opening movement of the door, said spring having a limited compression and serving as a stop when compressed to its limit, substantially as described.

2. The combination with the screw-threaded stem a flattened at a' and provided with the detent-lug a^2 , of the reversible angle-bracket b , b^2 , the bell c adjustably securable on said stem a , the spring f between said bell and said bracket b , and the bell-crank lever g connected to the bell-lever f' and actuating the said bell under the initial opening movement of the door, the said parts operating substantially as described.

3. The combination with the detent securable between the free edge of a door and its frame, of a bell, a nut and a spring on the said stem, said spring permitting a limited opening movement of the door and then acting as a stop, and bell-actuating connections operated by the initial opening movement of the door, substantially as described.

In testimony whereof I affix my signature in presence of two witnesses.

ANTHONY L. SHORE.
